CONNECTOR FOR VACUUM CLEANER
DUST BAGSEdgar P. Turner, Fanwood, N. J., assignor to The
Singer Manufacturing Company, Elizabeth,
N. J., a corporation of New Jersey

Application October 21, 1947, Serial No. 781,106

9 Claims. (Cl. 285—70)

1

This invention relates to vacuum cleaners and more particularly to means whereby the dust bag of a vacuum cleaner can easily be secured to or released from engagement with the exhaust outlet of a vacuum cleaner, and this invention has for one of its objects the provision of an improved device of this class.

Another object of the invention is to provide an improved bag coupling means for vacuum cleaners, wherein the portion of the coupling carried by the bag is inexpensive and therefore can be discarded whenever it becomes desirable to throw away the bag.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings—

Fig. 1 is an elevational side view of a vacuum cleaner embodying this invention;

Fig. 2 is a view as seen substantially in the direction of the arrow 2 of Fig. 1, and showing one side of the mouth of the dust bag held in contact with the exhaust port of the vacuum cleaner;

Fig. 3 is a sectional view taken substantially on the line 3—3 of Fig. 1 and looking in the direction of the arrows;

Fig. 4 is a detail view as seen in the direction of the arrow 4—5—6 of Fig. 3 and depicts, from another viewpoint, the same condition illustrated in Fig. 2;

Fig. 5 is a view similar to Fig. 4 but showing the mouth of the bag partly drawn down to engage the exhaust port of the vacuum cleaner;

Fig. 6 is a view similar to Figs. 4 and 5 but with the mouth of the bag clamped into engagement with the exhaust port of the vacuum cleaner;

Fig. 7 is a fragmentary view showing the mouth of the bag clamped into engagement with the exhaust port;

Fig. 8 is a fragmentary sectional view taken on the line 8—8 of Fig. 2; and

Fig. 9 is a view showing one side of the bag mouth before it is connected to the exhaust duct of the vacuum cleaner.

In the preferred embodiment of the invention, the vacuum cleaner illustrated in the drawings comprises an ambulatory chassis 11 supported on

2

front wheels 12 and back wheels 13. A propelling and guiding handle 14 is pivotally attached to the chassis by a pair of screws; one of which is shown at 16. A motor-driven fan unit (not shown), of any suitable type, is housed within the chassis 11 and this motor-fan unit functions to pick-up dirt from the floor and discharge it through an exhaust duct 17 formed in a rectangular rearward portion of the chassis 11. This duct 17 is rearwardly inclined downwardly and is formed by four walls comprising an upper wall 18, a bottom wall 19 and a pair of side walls 21 and 22. The four walls, just mentioned, terminate in surfaces 28, 29, 31 and 32 which, when taken collectively, form a rectangular apertured terminal surface which lies in a plane that is inclined forwardly with respect to a vertical plane passed therethrough. The bottom wall 19 adjacent the surface 29 carries two spaced lugs 33, which project beyond the plane of the terminal surface 29 and thereby provide an abutment for one side of the end of a vacuum cleaner dust bag 34, presently to be described. The side wall 21 carries an L-shaped angle bracket 36 secured thereto by a pair of rivets 37. One leg of the angle bracket 36 overlies the terminal surface 31 and thereby provides a recess 38 into which a portion of the above mentioned dust bag is placed. The other side wall 22 carries a trunk latch 39 having a fixed pivot plate 41 which is held to the wall 22 by a plurality of screws 42. The plate 41 has a pair of lugs 43 which support a pivot pin 46 on which is pivotally mounted a handle arm 47. The arm 47 carries a pivot pin 48 on which is pivoted one end of a latch plate 49. The free end of this plate is hook shaped as at 51 and thereby is arranged to engage and hook a portion of the bag 34.

The mouth of the bag 34 has a rectangular spring-wire frame, the four sides of which are designated as 58, 59, 61 and 62. The material from which the bag 34 is made, is folded back on itself and thereby forms a pocket 63, closed by a line of stitches 64, for retention of the wire frame.

The upper and lower sides 58 and 59 of the wire frame are preformed to be outcurved with respect to the bag mouth and from Figs. 4 and 5 it will be noted that the side 62 is preformed to be incurved, and from Fig. 9 it will be noted that the side 61 is also preformed to be incurved. In other words, the outcurved sides 58 and 59 are curved outwardly in the direction that would be taken by dirt passing from the bag cavity outwardly through the mouth, whereas, the in-

curved sides 61 and 62 are curved inwardly in a direction that would be taken by dirt passing through the mouth into the bag cavity. These permanent curvatures, which are formed into the four sides of the wire frame, insure that a tight joint will be made around the entire periphery of the bag mouth when it is in contact with the surfaces 28, 29, 31 and 32, because when the bag mouth is in clamped position the four curved portions of the wire are stressed and thereby act as clamps to hold the bag mouth in proper position.

The operation of connecting the mouth of the bag 34 to the exhaust duct 18 of the vacuum cleaner is as follows: The side of the bag mouth which encloses the incurved wire frame side 61 (Fig. 9) is placed adjacent the L-shaped bracket 36. The wire frame is then pressed until the side 61 is substantially straight. When this is accomplished the portion of the bag containing wire 61 (Fig. 2) is forced into the recess 38 between the overhanging end of the bracket 36 and the surface 31 of the end of the duct 17. The mouth of the bag 34 then assumes the position shown in Figs. 2 to 4. Under these conditions the wire 61 is straight and therefore is stressed. Thereafter the portion of the bag mouth which carries the wires 58 and 59 are forced into contact with the surfaces 28 and 29 and the hook 51 of the latch 39 is hooked over the portion of the bag mouth that encloses the wire portion 62, this condition being shown in Fig. 5. Next the latch 39 is moved from the hooked position of Fig. 5 to the fully closed position of Figs. 6 and 7. This straightens out and stresses the wire 62 and causes the portion of the bag mouth enclosing this wire to be clamped down against the surface 22.

From the above it will be noted that various curved portions of the wire frame when straightened and stressed function to press the entire periphery of the bag mouth against the exhaust outlet surfaces when only two sides of the bag mouth are clamped. This seals all openings between the exhaust outlet 17 and the mouth of the dust bag 34. The lugs 33 do not function as clamps but simply provide a convenient means for properly locating the bag mouth with respect to the bracket 36 and the latch 39. It will also be noted that the cloth or other material from which the bag is made acts as a gasket to prevent the undesirable escape of dirt being blown into the bag 34.

Having thus set forth the nature of the invention, what I claim herein is:

1. A connector means for coupling the mouth of a dust bag to the exhaust outlet of a vacuum cleaner, comprising, a pocket stitched into an end of said dust bag, a spring wire frame retained in said pocket and preformed to assume a curved shape, means for attaching a portion of said frame while retained in said pocket to the vacuum cleaner exhaust outlet, and means for stressing and bending the preformed frame whereby when the frame is so bent it seals all openings between the exhaust outlet of the vacuum cleaner and the mouth of the dust bag.

2. A connector frame for coupling the mouth of a dust bag having a dust receiving cavity to the exhaust outlet of a vacuum cleaner, comprising, a rectangularly shaped spring wire frame having a plurality of side portions sewed into the dust bag, some of the side portions of the wire frame being incurved with respect to the bag

cavity and other of the side portions being outcurved with respect thereto.

3. A connector frame for coupling the mouth of a dust bag having a dust receiving cavity to the exhaust outlet of a vacuum cleaner comprising a rectangularly shaped spring wire frame having four side portions sewed into the dust bag, two of the side portions of the wire frame being incurved with respect to the bag cavity and the other two side portions being outcurved with respect thereto.

4. A bag connector mechanism for attaching a dust bag having a dust receiving cavity to the exhaust outlet of a vacuum cleaner comprising, a rectangularly shaped spring wire frame having four side portions sewed into the dust bag, two of the side portions of the wire frame being incurved with respect to the bag cavity and the other two side portions being outcurved with respect thereto, a fixed angle bracket arranged to hold one of said incurved wire frames in a straight stressed condition, and a movable hook clamp arranged to draw the other three sides of the wire frame into a straight and therefore stressed condition.

5. A connector for coupling the mouth portion of a dust bag to the exhaust outlet of a vacuum cleaner comprising a rectangular shaped flat surface formed on the exhaust outlet of the vacuum cleaner; a rectangularly shaped, incurved and outcurved wire frame sewed into the mouth portion of said dust bag, means for aligning said mouth of the dust bag with the rectangularly shaped flat surface; and means for clamping said mouth to said flat surfaces.

6. A connector for coupling the mouth portion of a dust bag to the exhaust outlet of a vacuum cleaner comprising a rectangularly shaped incurved and outcurved spring wire frame sewed into the mouth portion of the dust bag; a hook carried by the exhaust outlet of the vacuum cleaner and arranged to engage an incurved portion of said wire frame; and a latch also carried by said exhaust outlet and arranged to engage another incurved portion of said wire frame.

7. A connector for coupling the mouth portion of a dust bag to the exhaust outlet of a vacuum cleaner comprising a spring wire frame sewed into the mouth portion of the dust bag; a hook carried by the exhaust outlet of the vacuum cleaner, the said hook being arranged to engage one edge of said dust bag mouth; and a latch also carried by said exhaust outlet and arranged to engage the other side of said dust bag mouth.

8. A connector means for securing a dust bag having a rectangular mouth to a vacuum cleaner, comprising, a rectangular duct having a top wall, a bottom wall and spaced side walls, the ends of said walls forming an apertured rectangular surface lying in one plane; an angle bracket carried by one of said side walls and having a portion overlying a part of said rectangular surface; a trunk latch mechanism carried by the other of said side walls and having a hooked portion that is mounted so as to be movable toward and away from another portion of said rectangular surface; a pocket formed around the rectangular mouth of said dust bag; and a rectangular frame sewed into said pocket, said frame having a pair of opposite members that are incurved with respect to said bag and having a pair of opposite members that are outcurved with respect to said bag, one of the incurved members being insertable between the overhanging portion of said angle bracket and said rec-

tangular surface, and the other incurved member being engageable by said hook.

9. A connector for coupling the mouth portion of a dust bag having a dust receiving cavity to the exhaust outlet of a vacuum cleaner, comprising, a rectangular spring wire frame secured around the mouth portion of the dust bag, two sides of said rectangular frame being outcurved with respect to said bag cavity; a hook carried by the exhaust outlet of the vacuum cleaner, said hook being arranged to engage one edge of said dust bag mouth; and a latch also carried by said exhaust outlet and arranged to engage another side of said dust bag mouth.
